(57) **CLAIM**

The ornamental design for a roofing shield, as shown and described.

DESCRIPTION

FIG. 1 is a front perspective view of a roofing shield showing the new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a front perspective view of an alternate configuration of the roofing shield of FIG. 1, with the roofing shield extended;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top view of FIG. 8;

FIG. 14 is a bottom view of FIG. 8;

FIG. 15 is a front perspective view of the roofing shield of FIGS. 1 and 8 in a collapsed form;

FIG. 16 is a front view of FIG. 15;

FIG. 17 is a rear view of FIG. 15;

FIG. 18 is a left side view of FIG. 15;

FIG. 19 is a right side view of FIG. 15;

FIG. 20 is a top view of FIG. 15; and,

FIG. 21 is a bottom view of FIG. 15.

The broken lines depict portions of the roofing shield that form no part of the claimed design. The broken lines in FIGS. 1 and 8 illustrating an air conditioning unit depict environment that forms no part of the claimed design. The broken lines in FIG. 17 depict portions of the signage that form no part of the claimed design. Furthermore, Applicant notes that the markings on the drawings are for shading purposes only, and are not to be considered a part of the design of the present invention.

1 Claim, 12 Drawing Sheets
